UNITED STATES PATENT OFFICE.

FLOYD E. LANE, OF FALCONER, NEW YORK.

IRONING BOARD.

Application filed October 24, 1923. Serial No. 670,578.

To all whom it may concern:

Be it known that I, FLOYD E. LANE, a citizen of the United States, residing at village of Falconer, in the county of Chautauqua and State of New York, have invented certain new and useful Improvements in Ironing Boards, of which the following, taken in connection with the accompanying drawings, is a specification.

This invention relates to an improvement in an ironing board and more particularly to one of the collapsible or folding type.

The primary object of this invention is to provide in a device of this character, novel and improved construction of supporting means by which the board can be easily opened into the position of use and can be automatically held in any one of certain adjustable positions.

Other objects will appear from a consideration of the following specification taken in connection with the drawings which form a part thereof and in which

Fig. 1 is a side elevation of one embodiment of this invention in the position of use.

Fig. 2 is a bottom view of the embodiment shown in Fig. 1 in the collapsed position.

Fig. 3 is a sectional view taken along the line 3—3 of Fig. 2.

Fig. 4 is a cross-section taken along the line 4—4 of Fig. 2.

Referring to the drawings, the reference numeral 10 is employed to designate an ironing board of any desired conformation suitably supported by pivotally joined legs 11 and 12. The legs 11 are pivotally mounted upon block 13 rigidly secured to the under side of the board adjacent its base. The legs 11 are preferably two in number connected by suitable cross-pieces 14, and as shown particularly in Fig. 1 extend to the front of the board so that for this reason they will be hereinafter referred to as the front legs. The legs 12 are also two in number and are carried by a cross shaft 15, pivotally mounted and extending through the legs 11. The legs 12 are united by cross-pieces 16 and are carried by and extending from them is a brace or support 17 which is firmly attached to the shaft 15, and to one of the cross-pieces 16. The brace 17 extends between the legs 11 and 12 and engages the under side of the board adjacent the nose in the manner to be described later.

On the under side of the board 10 are provided a pair of parallel longitudinally extending ribs or cleats 18 with which the brace 17 co-acts. Each of the ribs 18 comprises a strip 19 and a plate 20 which is rigidly secured thereto. The ends 21 of the strips 19 with which the plate 20 engage are extended to provide continuous longitudinal slots 22 shown particularly in Figs. 1 and 3. The upper wall of each slot 22 is formed by the strip 19 which is provided with a notch 23 and a plurality of rearwardly inclined notches 24. The brace 17 is secured to the ribs 18 by means of a pin 25 extending through the end of the brace and into the slots 22 along which it travels freely. The ribs 19 and notches 23 are so located that when the board is in the collapsed position shown in Figs. 2, 3 and 4 the pin 25 will rest in the notches 23. When, however, the board is erected in the position for use the pin 25 will rest in one of the sets of notches 24. In Fig. 1 of the drawing the pin is shown resting in the notches 24 nearest the notches 23 and the board is supported in its lowest position. If it is desired to have the board higher the legs 11 and 12 may be drawn together until the pin 25 leaves the first set of notches 24 and traveling along the slot 22 enters one of the other sets of notches 24.

While ironing boards of the adjustable type have been previously made it has been impossible to set them up without difficulty. A board made in accordance with my invention however, can be easily erected by placing the toe upon the end of the legs 11 and lifting the nose to swing the board around the pivot of the legs 11 on the block 13, the pin 22 leaving the notches 23 and bearing upon the plates 20 in the slots 22 until approximately the desired position has been reached. The board is then lowered and the pin 25 will slip from the slot 22 into the nearest notches. When the board is to be collapsed, the operator places the toe against the rear legs 12 and after lifting the nose until the pin 25 leaves notches with which it is in engagement and enters the slot 22 the board can then be lowered into the collapsed position the pin 25 traveling through the slot 22 into engagement with the notches 23 so that the legs and brace can lie against the under side of the board (see Fig. 3).

While one embodiment of this invention has been shown and described, I am not to

be limited thereto since it is obvious that others may be made without departing from the spirit and scope of the invention as set forth in the following claim.

5 Having thus set forth my invention, what I claim as new, and for which I desire protection by Letters Patent is:

In an ironing table, a board, a pair of spaced parallel front legs pivoted at one end 10 to the board and engaging the floor at their opposite ends, a cross-shaft connected to the front legs at points between the ends thereof, a pair of parallel short rear legs resting at their lower ends on the floor and pivoted at 15 their upper ends to said cross-shaft and being guidingly engaged by the sides of the front legs, a pair of parallel ribs depending from the board and having downwardly

facing notches, a cross piece connecting the rear legs intermediate the ends thereof, a single brace secured to the center of said cross-piece at its lower end, said cross-shaft extending through said brace between the ends thereof to support the same, and a pin carried by the upper end of the brace and having its ends projecting beyond opposite sides of the brace and receivable in the notches of the ribs, the ribs being spaced but slightly in excess of the thickness of the brace and receiving the upper end of the brace therebetween so as to engage opposite sides of the brace and to afford guides therefor.

In testimony whereof I have affixed my signature.

FLOYD E. LANE.
